UNITED STATES PATENT OFFICE.

EDWIN S. WOEHR, OF GENESEO, ILLINOIS.

DESIGN FOR A BOOK-HOLDER.

SPECIFICATION forming part of Design No. 33,293, dated October 2, 1900.

Application filed September 5, 1900. Serial No. 29,093. Term of patent 3½ years.

To all whom it may concern:

Be it known that I, EDWIN S. WOEHR, a citizen of the United States, and a resident of Geneseo, in the county of Henry and State of Illinois, have invented and produced a new and original Design for a Book-Holder, of which the following is a specification, reference being had to the accompanying drawing, forming a part thereof, in which is shown a perspective view of a book-holder embodying the features of my design.

The base A of the holder approximates a parallelogram, and at the corners of the base laterally and vertically extending members B and C are formed, opposing lateral members

extending outward in opposite directions. The members C are at an angle to the base A and also at an angle to the members B.

Having thus described my invention, I claim as new and desire to secure by Letters 20 Patent—

The design for a book-holder herein shown and described.

In testimony whereof I have signed my name to this specification in the presence of 25 two subscribing witnesses.

EDWIN S. WOEHR.
